United States Patent Office

Des. 188,862
Patented Sept. 20, 1960

188,862

CHRISTMAS TREE HOLDER OR SIMILAR ARTICLE

Oscar J. Krastel, Columbus, Ohio, assignor to Capital
Die Tool & Machine Company, Columbus, Ohio, a partnership

Filed Dec. 29, 1958, Ser. No. 53,943

Term of patent 14 years

(Cl. D35—3)

Fig. 1 is a perspective view of a Christmas tree holder or similar article showing my new design;

Fig. 2 is a side elevational view;

Fig. 3 is a horizontal sectional view taken along the line 3—3 of Fig. 2;

Fig. 4 is a bottom plan view thereof; and

Fig. 5 is an enlarged, fragmentary, vertical sectional view taken along the line 5—5 of Fig. 3.

I claim:

The ornamental design for a Christmas tree holder or similar article, substantially as shown.
